GARMENT HANGER RACK

Wallace C. McDermott, Washington, D. C.

Application May 10, 1937, Serial No. 141,829

7 Claims. (Cl. 211—49)

The invention relates to racks for holding garment hangers and has as an object the provision of a device of this character which will hold a considerable number of garment hangers, keeping them in order and available for convenient use.

It is a further object of the invention to provide a rack upon which garment hangers may be stored or upon which they may be shipped for sale.

Further objects of the invention will appear from the following description when read in connection with the accompanying drawing showing an illustrative embodiment of the invention, and wherein:

Figure 1 is a front elevation showing the device with one hanger in place;

Fig. 2 is a side elevation of the structure of Figure 1; and

Figs. 3 and 4 are detail sections on lines 3—3 and 4—4 respectively of Figure 1.

In the use of garment hangers in manufacturing and merchandising establishments it is the usual practice to throw the hangers into a bin when garments are taken off from them, and the hooks in the mass of hangers become entangled so that it is difficult to speedily remove a hanger from the mass when wanted for use.

To keep the hangers in order and ready to be easily secured when wanted, the rack of the invention comprises a pair of rods 10, 11 desirably of metal. For a rack to hold substantially fifty hangers of the type shown at 12, the rods 10, 11 if of metal may be made about one-fourth inch in diameter and desirably of metal that is resilient.

At one end each of the rods 10, 11, which are normally spaced apart, are curved as at 13, 14 to be brought into close juxtaposition and extend as at 15 a slight distance in parallelism downwardly, being then turned upwardly at 16 to provide the portions 17, 18 parallel and in substantial contact.

The upper portions of the rods 10, 11 as shown in Figure 1 are made to converge as at 19, 20 and are formed to a T-head, which may be done by bending the terminals thereof outwardly to provide the outward standing stub shafts 21, 22. The portions of the rods where they are parallel just below the T-head may be welded or pressed together.

A handle and locking device is shown in the form of a D handle member 23 provided with eyes 24, 25 taking over the stub shafts 21, 22 and revoluble thereon.

The upper ends of portions 17, 18 of the frame of the rack are shown as notched as at 26 and terminating slightly above the stub shafts 21, 22. A spring member 27 is shown pivoted at 28 to the loops 24, 25 as shown in Figure 3 eccentrically to the axes of stub shafts 21, 22.

The spring 27 is formed into a bail at 29 and the eccentric connection to the loops 24, 25 will have the result that when the handle 23 is swung to the upright position shown in Figures 1 and 2, the bail 29 will be pressed into the notch 26, thereby urging the members 17, 18 toward the T-head of the rack. On the other hand, when the handle is swung to the position indicated by dotted lines in Figure 3, the bail 29 will be caused to move in the dotted line path indicated in Figure 3 to release the upper ends of the members 17, 18 and to provide a free path for entry of the wire 30 of hangers 12 between said members 17, 18.

A loop or eye 31 is desirably provided upon the rack spaced from the upper portion thereof a sufficient distance to not interfere with the movement of the handle 23. When the rack is empty it may be hung upon the wall by the loop 31 and as fast as garment hangers become out of use, the wire 30 thereof is inserted between the free ends of rods 17, 18 and may be pressed downwardly to the point indicated at 32, Figure 1, and subsequent hangers may be forced down into contact with the present hanger until the rack is full. The hangers will be placed into the rack with the hooks all in one direction. When the rack is full, it may be locked by movement to vertical position of the handle 33 and may then be stored or transferred to a position where hangers are desired for use.

When wanted for use, the entire contents of the rack may be hung upon a horizontal rod by a single movement and the rack may then be pulled off from the hangers, leaving the whole of the hangers upon the rod ready for use.

It is contemplated that the invention may be utilized for shipping its component of hangers from the factory where the hangers are produced, in which case the entire number of hangers in a merchandising establishment will have a home in a rack when they are not in use.

The parallel rods 10, 11 constitute the body of the device and obviously may be substituted by a slat or bar of wood, plywood, or other material. In this event, the equivalent of the portions 17, 18 should be resiliently attached to the lower end of the body of the rack.

Minor changes may be made in the physical

embodiment of the invention within the scope of the appended claims without departing from the spirit thereof.

I claim:

5. 1. A garment hanger rack comprising: a body portion; elongated clamp means resiliently secured at one end to, and extending parallel with said body portion; said clamp means being divided and adapted to receive hook wires of a plurality of garment hangers therebetween and means on the body portion engaging the other end of said clamping means whereby the bars of the hangers disposed between the clamp means and the body portion are resiliently clamped against said body portion.
10. 2. A garment hanger rack comprising: a body portion; a pair of rods parallel with each other and with said body portion and each resiliently secured at one end to said body portion; said rods adapted to receive the hook wire of a garment hanger therebetween and means engaging the other end of said rods thereby resiliently pressing the bar of the hanger disposed between the body portion and rods against said body portion.
15. 3. A garment hanger rack comprising: a body portion; elongated clamp means resiliently secured at one end to, and extending parallel with said body portion; said clamp means divided to receive the hook wires of a plurality of garment hangers therebetween; and means to resiliently and releasably secure the free ends of said clamp means to the body portion; whereby the bars of said hangers disposed between the body portion and clamp means are resiliently clamped against the body portion.
20. 4. A garment hanger rack comprising: a body portion comprising a pair of spaced rods converging and secured together at their ends; a pair of parallel, closely adjacent rods resiliently secured at one end of each to the corresponding end of said body portion rods, and adapted to receive the hook wire of a hanger therebetween and the bar of a hanger between said rods and body portion; and means on said body portion adapted to engage and secure the other end of said closely adjacent rods.

5. A garment hanger rack comprising: a body portion formed of a rod bent to provide members spaced apart throughout the major portion of their extent but converging to near proximity at the ends of said body portion; a handle pivotally secured at one end of said body portion and provided with a locking means; the free ends of the rod forming said body portion at the end opposite to said handle being bent back to extend substantially the full length of the body portion and centrally thereof, and adapted to be resiliently engaged by said locking means.

10. 6. A garment hanger rack comprising: a body portion formed of a rod so bent as to provide members spaced apart for the major part of said body portion but converging to close proximity at the ends of said body portion, said rod being bent to form an eye at one end of the body portion and adapted to receive a handle, a handle pivotally mounted in said eye and provided with 15 a resilient locking means; the free ends of said rod forming said body portion at that end of said body portion opposite said handle being bent back adjacent to each other to extend slightly beyond the handle end of said body portion and centrally 20 of said body portion, catch notches formed near the extremity of said free ends, and adapted to be engaged by said locking means.

25. 7. A garment hanger rack comprising: an elongated body portion; a pair of elongated resilient clamp members resiliently connected at one end of each in close proximity to each other to and adjacent an end of said body portion and extending parallel with and normally in close proximity to said body portion at the same side thereof; 30 said clamp members being disconnected from each other throughout their length and at their free ends to permit insertion of the hook wires of garment hangers between them at their free ends with the bars thereof between the body portion and members, and to be slipped downwardly therebetween; the resilience of said clamp members and connection acting to clamp the bars of said garment hangers against said body portion when said bars are so placed.
